UNITED STATES PATENT OFFICE.

DIMITRIOS PANTAZI, OF NEW YORK, N. Y.

CIGARETTE-PACKING MACHINE.

1,200,227.

Specification of Letters Patent.

Patented Oct. 3, 1916.

Application filed December 18, 1915. Serial No. 67,598.

To all whom it may concern:

Be it known that I, DIMITRIOS PANTAZI, a subject of the King of Greece, and a resident of New York, in the county of New York and State of New York, have invented certain new and useful Improvements in Cigarette-Packing Machines, of which the following is a specification.

This invention relates to improvements in machines for apportioning and packing small articles, particularly cigarettes, into their retail receptacles, such machine being adjunctive to that in which the articles are made.

15 The objects of the machine are:—To accurately apportion a predetermined number of articles from a reservoir containing a stock of the same; to enter the articles into a partially formed receptacle, folding and forming the walls thereof, prior to the entrance of the article; to inclose the receptacle within an outer container; to provide means for supplying a coupon or ticket together with the articles; to apply an adhesive to a 20 binding strip and cause the same to adhere in the manner of a seal for the package whereby it may not be opened without rupture; to apply or affix a revenue stamp, if it be required, and finally to bunch the packages in such condition that they may be readily packed for wholesale delivery. The attainment of these objects is accomplished by the novel mechanism hereinafter described, and shown in the accompanying drawings, 25 forming a material part of this specification and in which:—

Figures 1 and 2 present collectively, a plan view of the entire machine, the demarcation lines *a—a* appearing on the drawings, 40 representing the same plane on the machine. Fig. 3 is a partial front elevation of the delivery portion of the machine. Fig. 4 is an enlarged plan view of a slide upon which the containers are actuated. Fig. 5 is a sectional view, taken on line 5—5 of Fig. 4. Fig. 6 is an enlarged view of the conveyer actuating means in detail. Fig. 7 is a front elevation of the front end of the machine, as shown in Fig. 1. Fig. 8 is a partial sectional view taken on line 8—8 of Fig. 1. Fig. 9 is a transverse sectional view taken on line 9—9 of Fig. 1. Fig. 10 is a detail sectional view, drawn to an enlarged scale, the section being taken on line 10—10 of Fig. 1. Fig. 11 is

a transverse sectional view taken on line 11—11 of Fig. 1. Fig. 12 is a similar sectional view taken on line 12—12 of Fig. 1. Fig. 13 is a like sectional view taken on line 13—13 of Fig. 1. Fig. 14 is a plan view of the article receiving and conveying device, 60 and pusher used in connection therewith. Fig. 15 is a top plan view of the pasting and cutting device. Fig. 16 is a sectional view taken on line 16—16 of Fig. 15. Fig. 17 is a side elevational view of the same. Fig. 18 65 is a detail view of the knife operating device, drawn to an enlarged scale. Fig. 19 is a fractional view of the knife operating crank. Fig. 20 is a top plan view of the coupon operating mechanism, and Fig. 21, 70 is a sectional view taken on line 21—21 of Fig. 20, showing the driving means.

It is to be understood that this machine is intended to operate upon completely formed cigarettes, that the boxes or containers consist of two parts, the outer of which is a flat rectangular tube adapted to contain a single row of cigarettes only. The inner or sliding element is delivered to the machine in a blank condition to be seamed, 75 folded and inserted, these operations being performed progressively in the machine.

The structure is comprised of a frame 30, the lower part of which rests upon the floor or other level foundation and is formed 80 with a number of uprights 31, connected at their tops by longitudinal bars 32 extending from end to end of the machine and supporting the superstructure as will become more fully apparent.

A reservoir 35 in which are loosely contained quantities of the cigarettes is mounted near the front end of the machine, having an open bottom adapted to permit the discharge of a single row of cigarettes into 95 the carriers 36, which as shown in Fig. 8 are flat plates having thin partitions 37 extending slightly above its surface. These plates are carried by arms 38 rigidly attached to alternate links in the conveyer chain 39, 100 which passes over the sprocket wheels 40 and 42.

The driving sprocket 40 is rigidly secured to the shaft 41, the loose sprocket 42 revolving on the fixed stud 43, and the carriers 36 105 are caused to ride on the supporting rail 44.

Another sprocket wheel 45 is secured to the shaft 41 having upon it a chain 46 which

runs over the sprocket 47, rigid on the shaft 48, mounted in the frame and having near its outer end a sprocket 50 driving the chain 51 which runs over the sprocket 52 at the end of the machine. (See Fig. 3.)

These chains and sprockets are moved intermittently by means of a dog 55 engaging with each alternate link in the chain 46, the dog being caused to advance and recede a definite distance by a slide 56, (see Fig. 6) engaged by the link 57 to the crank 58 rigid on the shaft 60, the shaft being constantly rotated through the bevel gears 61 and 62 respectively, the latter of which is rigidly mounted on the horizontally disposed shaft 65 revoluble in bearings secured to the frame.

The shaft 65 is driven through the sprocket chain 66, positively engaged upon the main driving shaft 67, which has upon it the tight and loose pulleys 68 and 69 respectively.

A work bench or counter 70 is provided for the convenience of the operator, who stands adjacent and is expected to see that the cigarettes 25 lie uniformly in the grooves of the conveyers, their printed side, if there be one, being upward.

Attached to alternate links of the chain 46 are rigid arms 71, engaged with carriers 72 having low side walls narrowed along the front, slightly raised surface 73, and an open slot 72' formed through the surface 72 for receiving the seals, as will be later described. Mounted above these carriers is a fixed bin or container 75 holding a stack of the outer box elements, which are delivered one at a time upon the surface 72 by means of the slide 76 actuated by an eccentric 77 fast on the end of the shaft 65, through the lever 78 which engages at its upper end with a cross bar 79, one end of which actuates the slide 76, the other end being similarly connected through the slide 80, operating below another bin or container 81 holding the blanks from which the inner element of the box is formed, a weight 82 is used within the container to hold the blanks flat and press them downward so that as the slide 80 is reciprocated the vertical plate 83 will engage with the lowermost blank carrying it outward and depositing it upon the surface 73 of the chain actuated carriers. From this it will be seen that the outer elements rest upon a surface, 72, lower by the thickness of the material used than the surface 73, see Fig. 11.

Immediately upon the receipt of one of the blanks on the carrier 76 a flat plate 84 presses downward upon it causing the edges to be upturned on all four sides as they contact against fixed walls 86, the plate 84 being actuated through the lever 85, operated by suitable linkage through an eccentric 88 secured on the shaft 65, the boxes being ad-

vanced to the next stage where the sliding elements are partially inserted within the outer elements and then farther advanced to the feeding device at which point the cigarettes, moved by the carriers 36, which are held coincident with the open partially formed box, are pushed therein by the reciprocating movement of the plate 90, formed in the manner of a rack having grooves 91 suited to slide over the partitions 75 37 formed on the carriers 36. This pusher is actuated by means of the slide 92, at the outer end of which is attached the link 93 moved by the crank 94, secured to the bevel gear 95, the mating gear 96 being rigid on the driving gear 67.

In order that the cigarettes may be closely packed and caused to move together, a slide-way 97 having bevel side walls receives the cigarettes as they spread by the projections 37 and moves them so that they will be readily entered within the box disposed on the carrier 73 immediately adjacent at that time.

In the next stage the boxes are brought into contact with a fixed beveled edged closing finger 98 whereby the shorter inner cover 28 of the sliding element 27 is caused to fold over upon the cigarettes, the longer cover 29 being similarly turned over by the closing finger 99 as the box is advanced but before doing so a coupon or ticket 100 is deposited on top of the cigarettes 25, the same being cut from a roll 101 carried on the frame of the machine and fed through by mechanism whereby the proper length is delivered and a knife 102 caused to sever the coupon from the strip allowing it to drop down an inclined chute 103 and from thence to the cigarette box as can be seen in Fig. 21.

The roller feed and knife actuating mechanisms are driven through gearing 105 actuated by a chain 106 running over sprocket wheels, one of which is secured to the shaft 107, the other to the mechanisms direct. The shaft 107 in turn is driven by the sprocket chains 108 and 109 direct from the shaft 67; thus no slippage can occur and the machine be accurately timed to perform the function of cutting and delivering coincidentally with the presentation of the open cigarette box.

In the next successive stage the box is completed by pushing in the sliding element by means of the pusher 110 operated through the slide 111 driven by the crank 112, attached to the bevel gear 113 meshing with the mating gear 114 fast upon the main driving shaft 67. The boxes are then passed through the strip sealing device, best shown in Figs. 2, 15, 16 and 17, comprising a roll 120 of printed paper a strip 121 of which passes over a slide way 120', drawn by the feed rolls 200 and 201 and is severed by the knife 122 operated by the crank 203,

connecting rod 204, slide 205, and cross-head 206, guided by the vertical rods 208, and pressed to avoid lost motion of the springs 209. After severing the strip it is covered with an adhesive from the gum supplying rolls 123 and 124, supplied from the reservoir 125 as clearly indicated in Fig. 16. These strips are applied over the outer surface of the box through the openings 72' so as to cover the end of the sliding element, thereby holding it in position. The pusher 126 operates to move the boxes from the plates 72 into engagement with the strip supplying devices, comprised of elements 121 to 124 inclusive. This pusher is actuated by one of the prongs of an inverted, U-shaped bar 128, at the center of which is attached a sliding bar 129, operated by the crank 130 rotated by the gears 131 and 132 respectively, the latter of which is rigidly secured to the shaft 67.

The other prong of the bar 128 is similarly connected to a pusher 135 which acts simultaneously with the pusher 126 to transfer the sealed boxes from the surface 72 of the second carrier to the carriers 140, operated and driven by the chain 51 running over the sprockets 50 and 52.

The sealing mechanism is driven through the shaft 142, supported in brackets 143, secured to the frame work 32 of the machine, the shaft being driven through the chain and sprockets 144 and 145; the latter engaging with a sprocket 146 fastened directly upon the driving shaft 67.

After the transference of the boxes upon the carriers 140 they are moved into position to be operated upon by the revenue stamp applying device which is an exact duplicate of that for supplying the strip, disposed in a reversed position to it and is driven by the shaft 148, through the sprocket chain 150 from the sprocket 151 also fast upon the driving shaft 67.

A pusher 152, similar to but operating opposite to the pusher 126, brings the boxes into position with the revenue stamp applying device from which they are returned to their normal position by means of spring 122', as in the former instance. This pusher is caused to move back and forth by reason of the slide 153, actuated through the crank 156, attached to the gear 157 driven by the mating gear 158 upon the shaft 67.

After the stamp has been applied the carrier is advanced, as before indicated, to the final stage, where it is delivered by the pusher 170, operated by the bent rod 171 of the slide 172, through the crank 173, driven by the gear 174, which meshes with its mating gear fast upon the shaft 67.

The boxes are delivered upon the belt 175 down an inclined surface 176, in such manner that they lie closely adjacent and angularly disposed, so as to be received by an

operator as they are moved along and bunched ready for shipment.

In order that the boxes may not slip off the surface of the belt 175, it is provided with guides 177 adjacent to its edges, the belt running over the pulleys 178 and 179 respectively, the latter of which is driven through the ratchet wheel 180, actuated by a pawl 181, moved by the link 182, operating in the slide 183 and driven in turn by the crank 184 from the shaft 148.

In operation the reservoirs being filled the machine is started and an outer box element delivered to receive an inner element in a partially formed and filled condition; the box is then supplied with a coupon, the inner element fully inserted in the outer and passed to the binding or sealing devices where a strip is applied and then a revenue stamp affixed, after which the filled boxes are grouped and delivered ready for such disposition as may be desired.

All these several operations are performed automatically as the boxes are advanced from stage to stage and no hand labor required except such as incidental to the proper care of the mechanism employed.

Thus it will be seen that the reduction of labor is very considerable, that the operations are expeditiously performed and that the mechanism is of simple character, cheap to construct and operate.

Having thus described my invention what I claim as new and desire to secure by Letters Patent, is:—

1. In a packaging machine, a reservoir for the articles to be packaged, traveling carriers adapted to receive articles therefrom, means for actuating said carriers intermittently, other traveling carriers adjacent to the first mentioned carriers, a reservoir adapted to deliver one element of a two sectioned receptacle for containing the articles, a third reservoir containing the other element of the receptacle, means for partially forming the second element prior to the reception of the articles, means for inserting the second element within the first element of the receptacle, means for delivering a coupon in intimate connection with the articles, means for inserting the inner element within the outer, means for affixing a seal across one end of the receptacle, a third traveling conveyer, means for moving the receptacle from the second conveyer to the third conveyer, means for applying a revenue stamp to the articles on said third conveyer, and means for delivering the receptacles in a bunched condition.

2. In a packaging machine, the combination with a frame, a plurality of movable carriers mounted in said frame, each carrier being compartmented and adapted to receive a single article in each compartment, means for actuating the carriers intermit-

tently, a second plurality of carriers adjacent to the first carriers, said second carriers having each a high and low surface upon its face, means for delivering one element of a two part box upon each of said carriers, means for delivering the other element of the box, means for partially folding the second element and inserting within the first mentioned element, means for transferring articles from the first carriers to the partially closed box, means for delivering a coupon in close proximity to the articles, and means for fully closing the second elements and inserting within the first elements.

3. In a packaging machine, the combination with an article carrier and a container carrier, means for transferring a definite predetermined number of articles into said container in connection with a coupon, means for sealing said container and means for affixing a revenue stamp on the opposite side of the container from the seal.

4. In a packaging machine, a frame, endless carriers, supporting a plurality of individual partitioned plates, a goods supply, means for delivering a predetermined number of the goods to each of said plates, a second endless carrier coöperative with the first mentioned carrier, means for delivering one element of a two part box upon said second carrier, means for delivering the second elements of the box, means for partially folding said second elements, means for transferring articles from the first mentioned carrier to the partially folded box, means for fully closing the second element, means for applying an adhesive seal to the ends of the receptacle, whereby the two elements are held in relation one to the other, means for applying a revenue stamp the opposite edge of the receptacle and means for delivering the receptacles upon an intermit-

tently advancing carrier transversely mounted in the machine.

5. In a packaging machine, a plurality of open topped carriers, means for supplying the carriers with the articles to be packaged, other carriers having two definite surfaces one higher than the other, one element of the container being carried upon the lower section and the other element upon the higher section, means for transferring the goods from the first named carriers to the second element of the container, means for folding and inclosing the articles in the container, means for cutting, gumming and affixing a seal to the container, a third carrier, means for transferring the container from the second carriers to the said third carriers, means for cutting, gumming and affixing a revenue stamp to the opposite side of said container and means for delivering said container from the machine.

6. In a packaging machine, adapted to operate on a two part container, a plurality of carriers, means for moving said carriers intermittently, each of said carriers having an opening at its rear side, a strip paper roll mounted on said frame, means for cutting, gumming and affixing a definite length of the strip to each container through the mentioned opening, a third series of carriers mounted adjacent to the said second carriers, said carriers also having an opening upon their rear edges, a second strip roller and a second means of cutting, gumming and affixing a definite length of the strip to the opposite edge of each container and means for delivering said containers outwardly from the machine.

In testimony whereof I have signed my name to this specification.

DIMITRIOS PANTAZI.
